INLET SYSTEM FOR PAPER MACHINES

Frederick S. Seaborne, Harrison, Wis., assignor to
 Paper Patents Company, Neenah, Wis., a corporation of Wisconsin

Application January 29, 1941, Serial No. 376,460

2 Claims. (Cl. 92—44)

My invention relates generally to inlet systems for delivering paper stock to the wet ends of Fourdrinier machines, and it has particular relation to closed stock inlet systems of novel construction whereby paper stock may be delivered to Fourdrinier machines in an improved manner.

In the manufacture of paper, the terms "stock," "stuff," or "furnish" are used more or less synonymously to designate the water mixture or suspension, of pulp, sizing agents, and loading agents, which is delivered to the wet ends of the Fourdrinier machines. In the interest of simplicity, such water mixtures or suspensions will be hereinafter referred to as the "stock," although it would be proper to use either of the other two terms.

In paper making, the stock flows out in a wide stream onto the wire of the Fourdrinier machine where the water part of the stock is drained off while the suspended pulp material of the stock is deposited in a continuous web or sheet on the moving wire. This continuous web passes through the machine and is progressively dried and smoothed into finished paper in the well known manner.

Since the stock carries the pulp, sizing and loading materials which form the body of the paper sheet, it is apparent that, in order to obtain uniform distribution, the stock should be delivered to the Fourdrinier machine in a stream having a uniform velocity at the different parts of the cross section thereof, and in as evenly mixed condition as possible. For, if the parts of the stream have different velocities or the mixture is not uniform as it spouts out onto the wire, the paper forming material will not be distributed evenly and consequently the paper web will be correspondingly non-uniform.

In modern paper mills it is the practice to deliver the stock to the wet end of a Fourdrinier machine through closed stock inlet systems which have replaced the open head-boxes which were used in the older paper mills. These closed stock inlet systems comprise, essentially, a stock discharge opening formed over the breast roll of the Fourdrinier machine through which the stock spouts out onto the wire, an inlet pump operating to deliver a substantially uniform amount of stock, and a closed conduit system inter-connected between the stock discharge opening and the discharge side of the inlet pump. Such a closed conduit system usually consists of piping connected to the inlet pump, and some form of wide conduit means interconnected between the piping and the stock discharge opening. The part of the system forming this wide conduit means and the stock discharge opening is usually referred to as the "inlet," as distinguished from the entire stock delivery system.

In these closed stock inlet systems, it will be

seen that the stock leaves the discharge side of the inlet pump in a stream of relatively large circular cross section, and is subsequently discharged from the inlet onto the wire in a broad, thin stream which is substantially as wide as the wire or breast roll. Thus, on passage through the stock inlet system, the stock stream changes in shape from a relatively large, circular, cross sectional shape into a wide and thin cross sectional shape.

10 Heretofore, this transformation and spread out in stream shape on passage through the inlet system has received little or no specific attention and has not been completely satisfactory. Two of the most objectionable consequences have been 15 that (1) uniform and even agitation of the stock has not been completely maintained, thereby resulting in clotting and uneven concentrations of the web forming material, and that (2) the velocity of the stream as it flowed onto the wire has 20 not been equal in all parts thereof. That is, some parts of the stream flowed at different velocities than others thereby giving rise to "channeling."

The primary object of the present invention is 25 to provide an improved conduit system interconnecting the inlet pump and stock discharge opening of a closed stock inlet installation, whereby stock may be delivered to a paper machine through the discharge opening in a more evenly mixed condition throughout and with the velocity 30 of different parts of this stream being substantially uniform from side to side. In this manner, a much more uniform distribution of the pulp and other solid material of the stock is obtained on the wire with a corresponding increase 35 in uniformity of the paper web or sheet formed.

A further and an important object of my invention is the utilization of the full length of a stock inlet for transforming the stream of stock 40 into shape and evenness for discharge onto the wire of a Fourdrinier machine.

A further important object of the invention is 45 to provide an inlet of such design that when the normal operating amount of stock is being supplied therethrough, its velocity of flow through the conduit or passageway of the inlet will be at least as great as or exceed the scouring velocity. The expression "scouring velocity" is used to designate the velocity above which the pulp fiber, or other solid matter of the stock solution will 50 not settle out and become deposited to a material extent onto the walls or sides of the inlet conduit.

Still another object of my invention is to provide 55 a closed stock inlet system capable of accomplishing the foregoing objects and of such construction that the system has a very high efficiency in respect to frictional loss in the pumping of the stock therethrough.

Another important object of my invention is

the provision of a full-sized stock distributing roll with a closed center, whereby the usual stock distributing function is obtained without necessitating an enlargement in the cross sectional area of the thin or narrow fluid passageway through an inlet made according to this invention.

According to my invention two features of construction provide for the delivery of paper stock to a Fourdrinier machine in the improved manner. First, the fluid passageway of an inlet is made in such a manner that the cross sectional shape thereof is in the form of an elongated, narrow slot. The passageway has such a cross sectional area that, when a normal operating amount of stock is being supplied to the Fourdrinier machine, the velocity of flow through the inlet will exceed the scouring velocity. Secondly, constrictions are provided in the inlet passageway which serve as efficient mixing means, aiding materially in the maintenance of a uniform mixture and distribution of the stock as it flows through the inlet. These constrictions are preferably Venturi-shaped and are placed sufficiently close together to keep the whole volume of the stock alive and working.

The narrow dimension or thickness of the passageway in an inlet made according to this invention is substantially less than the diameters of distributing rolls ordinarily used for these purposes. If the conventional type of distributing roll were used in such an inlet, a substantial enlargement in the cross sectional area of the narrow stock passageway would be necessitated. Such an enlargement in area would be objectionable for it would form an area of low stock velocity where objectionable foaming and settling out of the stock would occur. However, by employing my improved form of distributing roll having its center closed off, such an enlargement in the fluid passageway is eliminated while at the same time the distributing roll functions in the normal manner.

For a more complete understanding of the nature and scope of my invention, reference may be had to the following detailed description taken in connection with the accompanying drawings, in which:

Fig. 1 is a partially sectional plan view of an assembled closed stock inlet system, embodying the features of my invention, connected to a Fourdrinier machine;

Fig. 2 is a fragmentary side elevational view of the inlet system shown in Fig. 1;

Fig. 3 is a sectional view taken on line 3—3 of Fig. 1;

Fig. 4 is an enlarged fragmentary and partially sectional view of the stock supply end of the inlet shown in Fig. 3;

Fig. 5 is a sectional view taken on line 5—5 of Fig. 3 showing the construction of the supply end of the inlet;

Fig. 6 is a view taken on line 6—6 of Fig. 4 showing the construction of certain adjustable valves connected in the supply piping;

Fig. 7 is a sectional view taken on line 7—7 of Fig. 6;

Fig. 8 is a fragmentary sectional elevational view of a distributing roll forming one embodiment of my invention;

Fig. 9 is a sectional view taken on line 9—9 of Fig. 8; and

Fig. 10 is a fragmentary sectional view of a modified lip construction forming part of stock

inlets made according to this invention and not including a distributing roll.

In Figs. 1 and 2 a closed inlet system, embodying the features of this invention, is shown interconnected between the wet end of a Fourdrinier machine, indicated generally at 10 and a stock screen discharge 11. The closed conduit system for delivering paper stock between the screen discharge 11 and the wet end 10 includes an inlet pump 12 connected in driven relationship with a pump motor 13. The inlet pump 12 and motor 13 are mounted as a unit on a block 14 under the floor 15, as shown in Fig. 2. The suction side of the inlet pump 12 is connected by a pipe 16 (Fig. 2) to the outlet opening 17 (Fig. 1) of the screen discharge 11. The screen discharge 11 has an overflow compartment 20 formed on the left hand side thereof and separated therefrom by a weir 21. The stock which has overflowed into the compartment 20 drains out to the "white water" through an outlet opening 22. The rate of stock supply to the screen discharge 11 is regulated by means of a controller 23 of the diaphragm type installed in the bottom of the overflow compartment 20. The diaphragm controller 23 operates by regulating the depth of the stock in the overflow compartment 20.

The inlet pump 12 draws in stock from the screen discharge 11 through the pipe 16 and discharges it through stock inlet piping 24 connected to the discharge side thereof. A flow regulating valve 25 (Fig. 1) is provided in one section of the piping 24 which serves to regulate and control the supply of stock flowing therethrough.

In order to progressively spread out or divide the stock stream flowing through the relatively large piping 24, a Y fitting 25' is connected at the end thereof, and a pair of elbow fittings 26 connect the two branches of the Y fitting 25' to two piping sections 27 of reduced diameter, as shown. The piping sections 27 in turn branch out through Y fittings 28 and elbows 29 into smaller diameter piping sections 30. The piping sections 30 finally branch out through four Y fittings 31 into eight smaller pipe sections 32 of the piping system. The direction of fluid flow through the piping system is indicated by the arrows applied thereto.

The stock delivery conduit system is completed by duck bill fittings 33 which interconnect the ends of the eight pipe sections 32 with the stock supply end 34 of a stock inlet, indicated generally at 35. The stock stream spreads out through the fan shaped passageways of the stock supply end 34 into the narrow passageway 36 of the inlet 35. The stock is finally discharged through the stock discharge opening 37 (Fig. 2) of the inlet 35 as a broad, thin stream onto the wet end 10 of the Fourdrinier machine. From Fig. 1, it will be seen that the narrow passageway 36 is substantially as wide as the breast roll 40, or the wire 41 of the Fourdrinier machine. A distributing roll 38 of novel construction and forming one part of this invention is disposed cross-wise of the fluid passageway 36 adjacent the stock discharge opening 37, as shown.

Although the distribution of the stock as it leaves the eight pipe sections 32 will be fairly uniform, some slight adjustment may be necessary from time to time. Accordingly, it has been found to be desirable to provide adjusting valves 42 in the pipe sections 32. Referring particularly to Figures 4, 6, and 7 of the drawings, it will be seen that the valves 42 are provided at

the connection of the Y fittings 31 and the pipe sections 32. The valves comprise a pair of rectangular plate members 43 and 44 each having a central opening or aperture corresponding in size to the inside diameter of the pipe sections 32. Slots 45 are provided in the four corners of each of the plates 43 and 44 so as to permit relative sidewise adjustment thereof, as shown in Figs. 6 and 7. Backing flanges 46 and 47 are drawn up on the back sides of the flanges of the Y fittings 31 and the pipe sections 32 by four bolts 50 passing therethrough as shown in Fig. 6. Suitable packing pieces 51 are inserted between the pipe flanges and the plates 43 and 44 to provide a fluid tight joint. Adjustment of the valves 42 is made by loosening the bolts 50 sufficiently so that the plates 43 and 44 may be slipped relative to each other. In this manner the orifices in the valves 42 formed by the superimposed central openings in the plates 43 and 44 are increased or decreased in size so as to in turn increase or reduce the stock flow therethrough. After the adjustment has been made the bolts 50 are re-tightened.

Referring to Fig. 3 of the drawings for a detailed description of the stock inlet 35, it will be seen that the inlet may be considered as being made up of three main parts, namely the stock supply end 34, the main body part 52 in which the fluid passageway 36 is formed, and the super-structure indicated generally at 53. The construction of the inlet 35 may be conveniently described by considering each of these main parts or sections in detail.

Referring to Figs. 3, 4 and 5, it will be seen that the stock supply end 34 of the inlet 35 consists of eight duckbill fittings 33 and a section 54 which forms an extension for each of these duckbill fittings. The section 54 comprises a pair of angle members 55 and 56 which extend across the back end of the body part 52 and are suitably fastened thereto. A bottom plate member 57 rests on the short leg 58 of the angle member 56 and extends across the back of the inlet. The plate 57 is supported by laterally spaced cross members 60. A member 61 is connected to back ends of the cross members 60 and extends at right angles to the back end of the plate 57.

Eight trapezoidal, slot-shaped passageways 64 are formed in the section 54. The bottom of each of these passageways 64 is formed of a lining plate 65 secured by countersunk screws (not shown) on the top of the bottom plate 57. The sides of each of the passageways 64 are formed by eight pairs of side members 66. And, the tops of the passageways 64 are formed of transparent, "Lucite" trapezoidal shaped plates 67. The different parts forming the passageways 64 are held in assembled relation by cross members 70. The cross members 70 extend over the Lucite plates 67, as shown, and a number of bolts 71 (Fig. 5) extend through the members 70 and bottom plate 57 along the outside of the passageways 64. The bolts 71 and cross members 70 hold the Lucite plates 67 and side members 66 together. The front and back of the tops of the passageways 64 are completed by the inserts 72 and 73 (Fig. 3) along the front and back edges of each of the Lucite plates 67. An angle member 74 extends across the back of the section 54 opposite the lower member 61 and is supported by a number of spaced apart vertical cross members 75 on the top of the section 54.

The side members 66 taper from their thick 75

end at the back of the section 54 into narrower ends at the front where the section 54 connects with the body 52. Thus, the passageways 64 become gradually narrower as they flare out and approach the connection with the back end of the main inlet body 52. The back end of each of the eight passageways 64 is connected to the end of one of the pipe sections 32 of the stock supply piping by a duckbill fitting 33, as shown. Vertical transverse webs 76 and 77 are provided on the top and bottom of each of the fittings 33 so as to give strength and rigidity thereto. The flanges 78 on the wide front ends of each of the fittings 33 are drawn up to the members 61 and 74 on the back of the supply end section 54 by a set of backing flanges 80.

It will be seen that the fluid passageways of the stock supply end 34 gradually change from circular sections to point A (Fig. 3) where the fittings 33 are connected with the piping 32, into narrow slot-shaped openings at the point B where the passageways 64 communicate with the passageway 36 formed in the main inlet body 52. Preferably, the cross sectional area of each of the passageways at the point A is substantially greater than the cross sectional area at B. This reduction in cross sectional area serves to promote or establish uniformity of flow of the stock into the passageway 36.

The main body portion 52 comprises a base 81 with two parallel upright side castings 82 upstanding therefrom. The interior of the section 52 is formed of a welded frame structure. The stock inlet passageway 36 is formed by spaced apart members 83 and 84 extending crosswise of the section 52 between the sides 82, and raised at an angle of about 35° with the horizontal. It will be seen that the cross sectional shape of the passageway 36 is that of an elongated slot. The bottom passageway member 83 is fastened at its back or right hand end to a plate 85 and is curved at its front end or top end into a section 86 which rests on a horizontal cross plate 87. The under part of the section 52 is formed of frame members 88, 89, 90, 91, 92 and 93 welded together as shown.

The upper part of the body 52 includes a horizontal top member 94 supported by frame members 95, 96 and 97 interwelded, as shown. The vertical support member 97 is welded at its lower end to a member 100. The members 85 and 100 form the back part of the section 52 to which the stock supply end 34 is connected.

For the greater part of passageway 36, the lower and upper passageway members 83 and 84 are parallel to each other. The upper plate 84 however, is bent down at its lower or right hand end so that the passageway 36 at the part 36a tapers down to the same width at B as the width of the openings 64 in the section 54 of the supply end 34. Smooth surfaced lining sections 101 and 102 are fastened by counter sunk screws (not shown) onto the floor plate 83 of the passageway 36. Likewise, smooth surfaced lining sections 103 and 104 are similarly fastened to the roof plate 84 of the passageway 36.

It has been found that by providing crosswise constrictions in the path of flow of the stock through the inlet 35, an increased distribution and uniformity in the stock flow is obtained. And the increased velocity of flow of the stock through the constricted sections serves to maintain controlled turbulence of the stock thereby giving a homogeneous suspension of the solid materials throughout. The volume and velocity of flow of the stock

as it leaves each constricted zone will be more uniform than the flow entering it. In the interest of increased fluid flow efficiency, these cross wise constricted sections are preferably Venturi-shaped. One or more of such Venturi-shaped constrictions may be provided in a stock inlet as may be found desirable. The provision of such constricted sections in the fluid flow passageway of a stock inlet for a Fourdrinier machine which serve to give increased uniformity of flow distribution and effect a controlled turbulence of the stock, forms an important feature of my invention.

Referring to Fig. 3, it will be seen that the tapering passageways 64 communicating with the tapering section 36a of the passageway 36 form one set of Venturi-shaped constrictions in the fluid flow passageway of the inlet 35, with the throat thereof being at the point B. It has been found desirable to provide at least one more Venturi constriction further along in the inlet 35. Accordingly, a pair of Venturi-shaped plates 105 and 106 are fastened crosswise of the passageway 36, in opposing relationship, as shown. The plates 105 and 106 are so shaped as to provide a true Venturi passageway. That is, the total inlet angle E is about 25° while the total outlet angle F is about 7° . This particular design serves to form the most efficient type of constriction in respect to the minimum loss in static pressure.

A blade 107 (Fig. 3) for cleaning and wiping the Fourdrinier wire 41, is supported by a holder 108 resting in a bracket 109 secured to the front of the frame member 91.

The superstructure 53 serves to complete the mouth of the narrow fluid passageway 36. The back part of the superstructure 53 comprises a pair of upright sides 110 upstanding on the opposite sides of the top of the inlet body part 52, and a deck or floor member 111. A machined bearing plate 112 is fitted beneath the underside of the member 111 and is adapted to slide on the top member 94 of the body part 52.

The entire superstructure assembly 53 may be shifted forwards and backwards, as indicated by the arrow 113, by means of a reversible motor 114 connected with a worm drive mechanism 115. The motor 114 and worm drive 115 are centrally mounted as a unit on the back of the inlet 35. Power is conveyed from the worm drive 115 through a pair of shafts 116 extending from opposite sides thereof, to a pair of worm gears 117. The shafts 116 are connected with the gears 117 through a pair of worms 118 provided on the outer ends thereof. Each of the two gears 117 is keyed to a shaft 119 having a screw 120 formed on the end thereof. The screws 120 turn in the threaded collars or eyes 121 fastened on the upright sides 110. As the shafts 119 with the screws 120 on the ends thereof turn, the collars or eyes 121 are worked backwards or forwards depending upon the direction of rotation, thereby shifting the superstructure 53.

After the superstructure 53 has been shifted to the desired position, it may be secured in place by tightening a number of bolts 122 which screw through the plate 94 into collars 123 integrally formed on the underside thereof. The shanks of the bolts 122 pass through slots 124 in the members 111 and 112 as shown and the heads of the bolts 122 draw down on the top of the plate 111.

In order to provide an enlargement in the mouth of the passageway 36 to house the dis-

tributing roll 38 a member 125 is welded at its lower edge to the end of the deck member 111 and at its upper edge to a horizontal member 126. The frame structure of which the plate 126 is a part consists of frame members 127, 128, 129, 130, 131, 132 and 133 welded together, as shown. This frame structure is fastened at its back to the vertical legs of angle members 134 and 135 extending crosswise between the sides 110.

The stock discharge opening 37 is formed by a stationary lower lip member 136 and an adjustable upper lip member 137. The upper lip 137 is pivotally supported at its back edge by a suitable clamp assembly 140 carried on the underside of a vertically adjustable bracket 141. The bracket 141 is supported by vertical shafts 142 having threaded sections 143 passing through posts 144 integrally formed in the brackets 145. Vertical adjustment of the bracket 141 is effected by turning the vertical shafts 142.

The front edge of the upper lip 137 is adjustably supported by a number of rods 146 which are pivotally connected at their lower ends to ears 147 on the top of the lip 137, and threaded at their upper ends into socket members 150. The socket members 150 are held in the underside of a beam assembly 151 extending across the front of the inlet 35. The beam assembly 151 is supported by the stub members 152 vertically adjustable in the bracket posts 153.

The distributing roll 38 is journaled at its opposite ends in suitable water-sealed bearings (not shown) which are carried in opposite sides of the superstructure 53. The distributing roll 38 serves to give a smooth distribution of the stock as it spouts out the stock discharge opening 37. As stated, it is important that the incorporation of the distributing roll 38 does require an enlargement in the cross sectional area of the stock stream flowing through the inlet 35. It has been found that by closing off the center or inside of the distributing roll 38, such an enlargement in cross sectional area of the stock stream is not required and that the distributing function of the roll is not impaired.

Referring particularly to Figs. 8 and 9, it will be seen that the distributing roll 38 comprises an outer cylinder 155 perforated with large holes 156. The center or inside of the solid wall cylinder 155 is closed off by a cylinder 157 coaxially mounted thereon. A pair of annular discs 158 at opposite ends of the roll 38 serve to support the outer perforated cylinder 155 in co-axial relationship with the inner cylinder 157. The ends of the outer cylinder 155 are undercut to receive the peripheries of the discs 158 which are held by screws 160 to the ends 161 of the inner cylinder 157. A pair of stub shafts 162 are provided in opposite ends of the roll 38 and serve as journals for the rotatable support of the roll 38. The shafts 162 are welded in the opposite ends 161 of the inner cylinder 157, as shown.

In order that there be no substantial increase in the cross sectional area of the passageway 36, the inside cylinder 157 of the distributing roll 38 should have such a diameter that the sum of the dimensions L and M in Fig. 3 is about equal to the narrow dimension D of the passageway 36. It will be understood that this relationship is not limited to being exact but that it may vary between limits which give the desired results.

The shape and design of the inlet passageway 36 constitutes an important feature of the invention. Crosswise, from one side of the inlet 35

to the other, the passageway has about the same width as the Fourdrinier wire 41 or the breast roll 40. Since the width of the passageway 36 is thus more or less fixed, the thickness or narrow dimension D is variable to give the proper cross sectional area. This cross sectional area should be such that when the normal operating amount of stock is being supplied to the Fourdrinier machine 10, the velocity of flow through the inlet 35 will be at least as great as or exceed the scouring velocity.

According to the well known hydraulic principle, the velocity of flow is increased by reducing the narrow dimension D and may be decreased by increasing the dimension D. The range of stock supply to the paper machine 10 is fairly definite, and the passageway 36 is designed so that the stock flow will be at least as great as the minimum scouring velocity when the minimum normal operating amount of stock is being supplied. It has been found that the minimum scouring velocity is about 1½' per second. As stated, by having the velocity of stock flow through the inlet 35 at least as great as the minimum scouring velocity, the solid matter of the stock will not settle out and the sides of the passageway 36 will be maintained in a clean condition. This increase in velocity of flow of the stock as it passes through the inlet 35 serves to reduce the time available for clotting of the pulp, and the internal turbulence of the high velocity stream acts to tear apart previously formed clots and to maintain an ideal dispersion. The overall narrow passageway 36, in combination with the Venturi constrictions therein together serve as mixing means for the stock as it flows through the inlet 35. It will be seen that the transformation of the stock into form for discharge through the opening 37 starts in the duckbill fitting 33 and is carried out through the supply end passageways 64 and the inlet passageway 36 in a streamlined manner. Thus, substantially the full length of the inlet 35 is utilized in transforming the stock stream into proper form and evenly mixed condition for discharge onto the wire 41 of the Fourdrinier machine.

Some of the more important dimensions of one successfully operated, working embodiment of the inlet 35 are as follows:

The internal diameter of the pipe sections 32 at A (Figs. 3 and 4) where they are connected with the stock supply end 34 is 4", and hence the cross-sectional area of each of the pipe sections 32 at A is 12.6 sq. in. Since there are eight pipe sections 32, the total cross sectional area of the conduit system at A is about 100.8 sq. in. The narrow dimension of the passageway 36 at B (Figs. 3 and 4) is $\frac{1}{8}$ ", while the breadth of the passageway 36 was about 15 feet. Therefore the cross sectional area of the conduit system at B is about 56.25 sq. in. Accordingly, it will be seen that the cross sectional area at A is substantially greater than the cross sectional area at B, as previously stated.

The passageway 36 has a substantially uniform breadth, from side to side, of 15 feet, and a width (dimension D, Fig. 3) of 1 $\frac{1}{8}$ ".

The throat of the Venturi constriction formed by the Venturi plates 105 and 106 has a dimension T (Fig. 3) of $\frac{1}{8}$ ", and each of the plates 105 and 106 has a width W (Fig. 3) of one foot.

The outer perforated cylinder 155 of the dis-

tributing roll 38 has a diameter of 8" while the inner cylinder 157 has a diameter of 6". The dimensions L and M (Fig. 3) between the outside of the inner cylinder 157 and the walls of the distributing roll enlargement are equal and each has a value of about 1 $\frac{1}{4}$ ".

The breast roll 40 and wire 41 of the Fourdrinier machine both have a length of about fifteen feet.

- 10 It is not essential in all cases that stock inlets made according to my invention be provided with distributing rolls, since the narrow stock passageways and constrictions therein often give sufficient distribution and mixing of the stock.
- 15 In Fig. 10 of the drawings, a portion of a modified form inlet 163 is shown which does not have a distributing roll incorporated in the mouth of its stock passageway 36'. As there shown, the narrow passageway 36' of this modified form of inlet 163 narrows gradually into a discharge opening 37' formed by a lower lip 164 and a vertical upper lip assembly formed by the elements 165 and 166. The position of the upper lip is adjustable forwards and backwards as indicated by the broken line outline thereof.
- 20 Since certain changes may be made in the foregoing constructions, and different embodiments of the invention may be made without departing from the scope thereof, it is intended that all matter shown in the accompanying drawings or described hereinbefore be interpreted as illustrative and not in a limiting sense.

I claim:

1. In paper making apparatus, a forming wire, 35 and inlet means for delivering a uniform, evenly mixed stream of liquid stock to and across the breadth of said wire, said inlet means comprising stock supply means, a nozzle for discharging stock on said wire, an elongated closed conduit having 40 a passageway of slot-shaped cross-section connecting said stock supply means and said nozzle, the major dimension of said slot approximating the width of the stock stream discharged through said nozzle, the minor dimension of said slot in a zone spaced from said discharge means, being 45 constricted in a manner to provide the passageway with a Venturi-shaped portion.
2. In paper making apparatus, a forming wire, a closed inlet for delivering liquid stock to said wire, said inlet comprising an elongated slot-shaped passageway of a breadth approximating the breadth of the stream of stock to be delivered to said wire, said passageway having the depth of a portion thereof adjacent its delivery end increased across its entire breadth to form a chamber, and a distributor roll rotatably mounted in said chamber and extending across substantially the entire breadth thereof, said distributor roll comprising an outer perforated cylinder, and an inner imperforate cylinder coaxial with said outer cylinder, the outside diameter of said inner cylinder being less than the inside diameter of said outer cylinder so as to permit stock to pass through the latter, said outside diameter of said inner cylinder being so related to the depth of said chamber that the combined cross-sectional areas of the passageway portions on opposite sides of said inner roll, approximate the cross-sectional area of the passageway portion leading into said chamber.

FREDERICK S. SEABORNE.
